EXHAUSTER FOR SPRINKLER SYSTEMS

William B. Griffith, Audubon, N. J., and David Arthur Keller, Drexel Hill, Pa.

Application May 14, 1935, Serial No. 21,364

13 Claims. (Cl. 169—17)

Our invention relates to improvements in dry pipe sprinkler fire extinguishing systems containing air under pressure for holding the dry pipe valve closed against water under a supply pressure. The invention particularly relates to systems including apparatus for rapidly exhausting the air pressure and for accelerating the opening of the dry pipe valve upon the opening of a sprinkler head.

10 Exhausters and accelerators now in general use employ a retaining chamber in communication with air under the system pressure, by means of a restricted orifice, of pin point dimension, through which the air pressure slowly equalizes due to leakage, and when a sudden reduction in the system pressure occurs, due to the opening of a sprinkler head, said restricted orifice retards the reduction of the pressure within said chamber and the retarded pressure is utilized to open an exhaust valve through which the system pressure is further reduced. Such devices have failed to operate due to the clogging of the orifice by the accumulation of foreign particles.

The object of our invention is to provide means for insuring the proper operation of the retaining chamber by eliminating the possibility of failure of operation due to the restricted orifice being obstructed.

A further object is to construct a retaining chamber with a connection containing a body of liquid which is movable therein for imparting the system pressure to air confined in the retaining chamber, and to actuate the exhaust valve by means movable by the expansive action of the pressure retained in said chamber by the inertia of the liquid, when there is a sudden reduction in the system pressure.

A further object is to provide a retaining chamber having a member movable by air confined under pressure within said chamber and provide a connection between said chamber and the system containing air under pressure, said connection containing a liquid for excluding said air from the connection below the level of the liquid, and for maintaining the connection free from foreign matter tending to clog the connection.

A further object is to provide said connection for containing the liquid with a sleeve formed of material impervious to corrosion due to the liquid, said sleeve forming a restricted orifice for the passage of liquid through the connection.

A further object is to associate a reservoir with the connection containing the liquid, in which reservoir the surface of the liquid is exposed to the air under the system pressure.

A further object is to provide actuating means of novel form between the movable member and the exhaust valve for opening said valve.

A further object is to provide a casing forming a pressure chamber and an inlet chamber, said pressure chamber encasing our improved retaining chamber, and liquid reservoir, and also the exhaust valve, said inlet chamber encasing a drain valve, together with novel means for actuating said valves.

These together with various other novel features of construction and arrangement of the parts, which will be more fully hereinafter described and claimed, constitute our invention.

Referring to the accompanying drawings:

Fig. 1 is a vertical sectional view of our improved exhauster, as on line 1—1 Fig. 2, and showing, diagrammatically the exhauster connected with a dry pipe system, in dot and dash lines.

Fig. 2 is a horizontal section on line 2—2 Fig. 1.

Fig. 3 is a vertical section on line 3—3 Fig. 1.

Fig. 4 is a perspective view of the pivoted member for actuating the exhaust valve, detached.

Fig. 5 is a perspective view of the exhaust valve 25 clapper, detached.

In the accompanying drawings in which like reference characters refer to like parts, 8 represents a combination accelerator and exhauster embodying our invention. A casing 10, comprises 30 sections 12, 13 and 14, which sections are secured together by fastening devices 15 and 16.

A diaphragm 18 is positioned between the sections 13 and 14, and its periphery is secured between flanges formed upon the sections 13 and 14.

The lower section 14 is provided with an inlet connection 20. A pipe 21, shown in dot and dash lines, connects section 14 with the riser pipe 22 of a sprinkler system shown diagrammatically. The system includes a dry pipe valve 25, connected with the riser 22 and a water supply pipe 26. The dry pipe valve may be of any well known type having an air clapper 27, a water clapper 28 and an intermediate, or neutral air chamber 29, formed between the clappers. The clappers are held closed against the water pressure in the pipe 26 by air under the system pressure contained in the riser 22 and the branch pipes having automatic sprinkler heads 30.

The section 14 of the casing 10 is provided with a drain aperture 32 for the connection of a drain pipe 33. A valve seat 34 is provided upon the section 14, and said seat surrounds the drain aperture 32. A drain valve 35 is normally held closed upon the seat 34 by a spring 36, in-

terposed between the valve and a bearing 37 supported by arms 38 from the walls of the section 14.

The drain valve 35 is secured upon a shaft 39, 5 movably mounted in said bearing 37. The upper end of the shaft is secured by means of clamp plates 40 and 41 to the diaphragm 18. The shaft 39 is provided with a small passageway 43 through which air under the pressure of the system may 10 slowly equalize on opposite sides of the diaphragm 18, thus permitting the spring to normally hold the drain valve 35 closed upon its seat. When the pressure is exhausted from the pressure chamber 45, as more fully hereinafter described, the system pressure in the inlet pressure chamber 46 will move the diaphragm 18 and lift the drain valve 35 against the action of the spring 36 and open the drain valve 35, thus allowing the air under the system pressure to 20 rapidly exhaust through the drain pipe 33.

The novel features of the present invention include a retaining chamber 48, comprising a receptacle 50 located within the pressure chamber 45, formed within the casing sections 12 and 25 13. The section 13 is provided with inwardly projecting lugs 52, 53 and 54, shown in Figs. 2 and 3. The receptacle 50 is provided with outwardly projecting lugs 55, 56 and 57, which are supported upon the lugs 52 to 54, of section 13, 30 by means of fastening devices 58.

The lug 52 is of hollow construction and forms an exhaust passage 60 and also a connection for a pipe 61, arranged to communicate with the intermediate chamber 29 of the dry pipe valve. 35 The lug 55 on the receptacle 50 has an aperture 62, which registers with the exhaust passage 60 formed through the lug 52. A gasket 63 forms an air tight joint between the facing surfaces of said lugs.

40 The exhaust passage formed through the lugs 52 and 55 is normally closed by an exhaust valve 64, comprising a tubular fitting 65, secured in the aperture 62 in the lug 55. Said fitting 65 is provided with a valve seat 66 for a clapper 67. 45 Said clapper has two arms 68 which are pivotally mounted upon a shaft 69 and which in turn is mounted upon a bearing 70 formed upon the wall of the receptacle 50. The clapper 67 is provided with a resilient gasket 71 for tightly 50 sealing the outlet through the valve seat 66 when the clapper is held in the closed position upon its seat by air under the system pressure within the chamber 45. The clapper 67 is opened in a manner hereinafter described.

55 The receptacle 50 forms a retaining chamber 48, said chamber is sealed by a movable member 73, which separates the retaining chamber from the pressure chamber 45. The movable member 73 is in the form of a diaphragm having its periphery secured upon the receptacle 50 by a clamp ring 74, secured to the receptacle by fastening devices 75.

A reservoir 78 is located within the pressure chamber 45 and is in communication with the 60 retaining chamber 48 through a passageway 79, formed within a connection 80, and through an aperture 81 formed through a tube 82 secured in the bottom wall 83 of the receptacle 50, by a packing gland 84.

70 The connection 80 is secured upon the under facing surface of the receptacle 50 by fastening devices 85. The reservoir 78 is entirely supported by the connection 80. A body of liquid 86, preferably mercury, is contained in the passageway 79 of the connection 80 and occupies the lower

portion of the reservoir 78 and the retaining chamber 48 and forms a seal for preventing the passage of air to and from the retaining chamber 48.

The surface of the liquid 86 in the reservoir 78 5 is subjected to the air under the system pressure and contained in the pressure chamber 45. The upper surface of the movable member 73 is also subjected to the air under the system pressure and contained in the pressure chamber 45. The 10 system pressure upon the liquid in the reservoir 78 causes the body of liquid to compress the air entrapped in the retaining chamber 48, between the surface of the liquid in said chamber and the inner surface of the movable member 73, so that 15 the pressure on opposite surfaces of the member 73 will slowly equalize by the liquid being forced to and from the retaining chamber 48, due to slow variations in the system pressure due to leakage. 20

The exhaust valve 64 is provided for controlling the flow of air from the chamber 45 under the system pressure. Said valve 64 is preferably located within the pressure chamber 45.

Mechanism is provided for opening the exhaust 25 valve 64 by moving the clapper 67 from its seat by a movement of the diaphragm, or movable member 73, when the latter is acted upon by a preponderance of pressure in the retaining chamber 48, upon the occurrence of a sudden reduction 30 of the system pressure due to the opening of a sprinkler head 30.

The reduction of the pressure in the pressure chamber 45 relieves the pressure from the upper 35 surface of the movable member 73, so that the expansive force of the air retained by the liquid within the chamber 48 will move the member 73 and actuate the mechanism for opening the exhaust valve 64.

The air pressure is retained in the chamber 48 40 for a relatively long period of time after a reduction occurs in the system pressure, due to the inertia of the liquid 86. The liquid flows slowly through the connection 80 from the retaining chamber towards the reservoir 78 when the air 45 pressure in the reservoir 78 is reduced by a reduction of the system pressure.

Any liquid such as water, oil, or mercury, may be employed for filling the passageway formed through the connection 80, between the retaining 50 chamber 48 and the reservoir 78.

The reservoir 78, retaining chamber 48 and the connection 80 are constructed of such capacity that they will contain sufficient liquid to insure the passageway and the tube 82 being submerged in the liquid at all times and under all variations of pressure, thus avoiding the clogging of the passageway 79 and the aperture 81 by the accumulation of foreign particles which would otherwise be carried by the air if it came 60 in contact with the passageway and the aperture 81. By thus always maintaining liquid in the passageway we eliminate the trouble heretofore experienced in devices having a restricted aperture for the passage of air between a retaining 65 chamber and the system pressure.

The reservoir 78 and the retaining receptacle 50 are positioned in spaced relation and the connection 80 is connected between and below the bottom portions thereof, thus a structure 70 of U-tube formation is provided for containing the liquid 86.

The passageway between the reservoir 78 and the retaining chamber 48 must always be kept open and free from corrosion and therefore we 75

employ a tube 82 which is formed of glass or porcelain for this purpose.

The tube 82 forms the restricted portion of the passageway between the reservoir and the 5 retaining chamber 48. The size of the aperture 81 through the tube depends upon the viscosity of the liquid employed. The greater the viscosity of the liquid the greater will be the diameter of the aperture required through the tube. 10 However the use of a liquid instead of air permits the employment of a relatively larger restricted orifice or aperture than the minute aperture, of pin point dimension, heretofore used in exhausters and accelerators for retaining the air 15 under pressure in the retaining chamber after the occurrence of a reduction in the system pressure.

Mercury has been found to be the most suitable liquid for carrying out our invention as it 20 will remain fluid at the ordinary temperatures to which sprinkler systems are subjected. A further advantage in the use of mercury is that all foreign particles will float upon the surface and will not be carried through the passageway 25 leading to the retaining chamber.

The novel mechanism for opening the exhaust valve 64 by the action of the movable member 73, comprises, a latch lever 88, pivoted upon a pivot pin 89, mounted upon bearings 90 and 91, 30 formed on arms 93 and 94 and forming part of the clamp ring 74. The opposite end of the lever 88 is pivotally connected by a pin 93 with a head 94, which is supported upon, or positioned adjacent to the movable member 73.

35 A rotatable member 96 is pivotally mounted on the shaft 69, on which the clapper 67 is pivoted. Said member 96 has a body portion 97 having two arms 98 and 99 which embrace the bearing 70 and also embrace the arms 68 40 formed on the clapper 67, whereby the clapper and the member 96 are rotatably mounted upon the shaft 69 and movable independently of each other. The member 96 is provided with an arm 100, to which one end of a spring 101 is attached. The opposite end of the spring is attached to a post 102, forming part of, or mounted 45 upon the clamp ring 74.

The rotatable member 96 is provided with a 50 segmental web 105, the upper portion of which forms a tooth 106 which normally engages a shoulder 107 upon the lever 88, whereby the lever acts as a trigger for holding the member 96 against the action of the spring 101. When the lever 88 is lifted by the upward movement 55 of the member, or diaphragm 73, the tooth 106 will be released from the shoulder 107, of the lever 88, and the spring will rotate the member 96 about its pivot pin 69.

The body portion 97 of the member 96, as 60 shown in Fig. 4, has two depending side bars 108 and 110, connected by a cross bar 112, and forming a loop which loosely embraces a tongue 113, formed upon the clapper 67. The tongue 113 projects into said loop and is normally positioned in spaced relation with body portion 97 and the cross bar 112, so that the clapper 67 can be moved by the action of air under pressure within the chamber 45, independently of the member 96, and thus compress the gasket 71, 65 carried by the clapper, against the valve seat 66. By this arrangement the clapper is normally held tightly closed upon the valve seat. 70

Another advantage of the enlarged loop upon the rotatable member 96 is that when the latter 75 is released from the lever 88 and is rotated by

the spring 101, said member 96 will have gained some momentum by the time the cross bar 112 takes against the tongue 113 of the clapper, whereby the impact of the cross bar against the clapper will assist the action of the spring 5 to open the clapper against any pressure remaining in the pressure chamber 45 and also to overcome any tendency of the clapper to stick upon its seat.

The upper section 12 of the casing is provided 10 with a removable plug 115, as shown in Fig. 2, which plug may be removed for making the exhaust valve 64 and the rotatable member 96 accessible, so that after the device has operated to exhaust the air from the sprinkler system, the 15 rotatable member 96 may be reset in engagement with the latch lever 88, thus allowing the exhaust valve clapper 67 to close upon its seat.

The reservoir 78 has a cap 116, provided with a threaded aperture 117, for the insertion of a plug, 20 not shown in the drawings, to retain the liquid in the reservoir during shipment. The plug may be removed from the cap 116 through the opening formed in the casing and occupied by the larger plug 115. 25

By removing the fastening devices 15 the top section 12 may be removed, thus making the receptacle 50 and the reservoir 78, and also the exhaust valve 64, accessible. By removing the fastening devices 58, shown in Figs. 2 and 3, the 30 receptacle 50, reservoir 78, and the exhaust valve 64 may be removed as a unit.

The operation of the invention is as follows: The air under the system pressure tends to keep 35 the drain valve 35 and the exhaust valve 64 closed, also the clappers 27 and 28 of the dry pipe valve closed. The air under the system pressure passes through the passageway 43 and equalizes the pressure in the chambers 45 and 46, on opposite sides of the diaphragm 18, during slow 40 changes in the pressure due to leakage.

The reservoir 78 is open to receive air under pressure through the aperture 117, equal to the pressure in the chamber 45 and this same pressure acts upon the upper side of the movable 45 member 73, which seals the chamber 48. The air under the system pressure acts upon the surface of the liquid 86 within the reservoir 78, and the liquid is moved through the connection 80, so that the body of liquid within the retaining 50 chamber 48 compresses the air within the chamber 48 against the under surface of the movable member 73, so that the latter will remain balanced between equal pressures on opposite sides of the member 73, and slow changes in the system 55 pressure will be compensated for by the movement of the liquid through the connection 80.

A sudden reduction of the system pressure, by the opening of a sprinkler head, reduces the pressure in the chambers 45 and 46. The reduction 60 of the pressure in the chamber 45 causes a reduction of the pressure upon the upper side of the movable member 73, the exhaust valve clapper 67 and also upon the surface of the liquid in the reservoir 78. The air under pressure will be 65 retained within the retaining chamber 48 by the retarded flowing of the liquid through the tube 82, from the chamber 48 toward the reservoir 78.

The relatively higher pressure retained in the chamber 48 will move the diaphragm or member 70 70 upwardly against the reduced pressure in the chamber 45. The upward movement of the member 73 will lift the latch lever 88 and withdraw the shoulder 107 from the tooth 106 of the rotatable member 96. The spring 101 will then 75

rotate the member 96 about the shaft 69 and the cross bar 112 will engage the clapper 67 and lift it from its seat and open the exhaust valve 64. The air under the system pressure will pass 5 through the exhaust valve and the connection 61 to the intermediate chamber 29 of the dry pipe valve and accelerate the opening of the clappers 27 and 28.

When the air pressure is exhausted from the 10 pressure chamber 45, by the opening of the exhaust valve 64, the system pressure still remaining in the inlet chamber 46 will act upon the under surface of the diaphragm 18, due to the small restricted passageway 43, and cause the 15 diaphragm 18 to lift the drain valve 35 from its seat, thus allowing all the air under the system pressure to rapidly exhaust through the drain valve 35. When the pressure again equalizes on opposite sides of the diaphragm 18, the drain valve 35 will be closed by the action of the spring 20 36, thus preventing the flow of water into the drain pipe 33, when the air is replaced by water throughout the system by the opening of the dry pipe valve.

25 Various changes may be made in the construction of the parts and the operation thereof without departing from our invention.

We claim:

1. An exhauster for a dry pipe sprinkler system comprising a pressure chamber adapted to contain air under the system pressure, a sealed 30 expandible air retaining chamber located in said pressure chamber and subjected externally to the pressure in said pressure chamber, a connection 35 having one end connected with said retaining chamber and its opposite end subjected to the pressure in said pressure chamber, a body of liquid in said connection and arranged for compressing the air in said retaining chamber relatively to the 40 pressure in said pressure chamber acting upon the liquid, said connection having a contracted portion for retarding the flow of the liquid, a valve controlling the flow of air from the pressure chamber, and valve actuating means operatively associated with said retaining chamber and arranged 45 for opening the valve by the expansion of the retaining chamber caused by the expansive action of the air retained in the retaining chamber by the inertia of the liquid upon the occurrence of 50 a sudden reduction in the pressure in said pressure chamber.

2. An exhauster for a dry pipe sprinkler system comprising a pressure chamber adapted to contain air under the system pressure, a sealed 55 expandible air retaining chamber located in said pressure chamber and subjected externally to the pressure in said pressure chamber, a U-tube having one end connected with the retaining chamber and its opposite end subjected to the 60 pressure in said pressure chamber, a body of liquid in the U-tube arranged for compressing the air within the retaining chamber relatively to the pressure in said pressure chamber, said U-tube having a reduced portion for retarding the flow 65 of the liquid and for retaining the air under pressure within the retaining chamber upon the sudden reduction of the pressure in said pressure chamber, a valve controlling the flow of air from the pressure chamber, and mechanism operatively associated with the retaining chamber and the valve for opening the latter by the expansion 70 of the retaining chamber.

3. An exhauster for a dry pipe sprinkler system comprising a pressure chamber adapted to contain air under the system pressure, a sealed ex- 75

pansible air retaining chamber located in said pressure chamber and subjected externally to the pressure in said pressure chamber, a U-tube having one end connected with the retaining chamber and its opposite end subjected to the pressure in said pressure chamber, a body of liquid in the U-tube arranged for compressing the air within the retaining chamber relatively to the pressure in said pressure chamber, a part 5 having a restricted orifice and forming part of the passageway through the U-tube and arranged for retarding the flow of the liquid from the retaining chamber, a valve controlling the flow of air from the pressure chamber, and mechanism operatively associated with the retaining chamber and the valve for opening the latter by the expansion 10 of the retaining chamber caused by the expansive action of the air retained under pressure by the liquid in passing through said restricted orifice upon the occurrence of a sudden 15 reduction in the pressure in said pressure chamber.

4. An exhauster for a dry pipe sprinkler system containing air under pressure comprising a pressure chamber adapted to contain air 20 under the system pressure, an air retaining chamber, a member movably mounted between and separating said chambers, said member subjected externally to the pressure within the pressure chamber, a restricted connection between 25 said chambers, a body of liquid occupying said connection, a valve controlling the flow of air from the pressure chamber, and means operatively associated with said member and the valve 30 for opening the latter by a movement of said member caused by the expansive action of air retained under pressure within the retaining chamber by the inertia of the liquid during a sudden reduction in the pressure in said pressure chamber.

5. An exhauster for a dry pipe sprinkler system comprising a pressure chamber adapted to contain air under the system pressure, an air retaining chamber located in said pressure chamber, a member movably mounted upon said retaining chamber and sealing the same said member subjected externally to the pressure within the pressure chamber, a connection having one end communicating with said retaining chamber and its opposite end exposed to air under the pressure in said pressure chamber, a body of mercury occupying said connection and movable therein by unequal pressure for equalizing the pressure on opposite sides of said member during 45 slow changes in the system pressure said connection arranged for retarding the flow of the mercury upon the sudden reduction in the system pressure, a valve controlling the flow of air from the pressure chamber, and means operatively associated with said member and the valve for opening the latter by a movement of said member caused by a preponderance of pressure in said retaining chamber.

6. An exhauster for a dry pipe sprinkler system comprising a casing adapted to contain air under the system pressure, an air pressure retaining chamber located in the casing, a member movably mounted upon said chamber and sealing the same, said member exposed upon its exterior to the pressure within the casing, a connection communicating with said chamber and with the pressure within the casing, a body of liquid occupying said connection, a tube formed of glass located in said connection and forming a re- 65 70 75

- stricted passageway for retarding the flow of liquid through said connection upon the occurrence of a sudden reduction in the pressure within the casing, a valve controlling the flow of air from the casing, and means operatively associated with said member and the valve for opening the latter by a movement of said member by a preponderance of pressure within said chamber.

7. An exhauster for a dry pipe sprinkler system containing air under pressure comprising, a pressure chamber adapted to contain air under the system pressure, an air pressure retaining chamber located in said pressure chamber, a member movably mounted upon the retaining chamber and exposed upon its exterior to the pressure in the pressure chamber, a reservoir having an open end and located in the pressure chamber, a connection between said retaining chamber and said reservoir, a body of liquid occupying said connection, said connection having a restricted orifice arranged to permit the slow flowing of the liquid to and from the retaining chamber for equalizing the pressure on opposite sides of said member and for retarding the flowing of the liquid, and means operatively associated with said member and arranged for exhausting the pressure from said pressure chamber by a movement of said member caused by the expansive action of the air retained in the retaining chamber by the liquid during a sudden reduction of the pressure within said pressure chamber.

8. An exhauster for a dry pipe sprinkler system containing air under pressure, comprising a pressure chamber adapted to contain air under the system pressure, an air pressure retaining chamber located in said pressure chamber, a member movably mounted upon the retaining chamber and exposed upon its exterior to the pressure in the pressure chamber, a connection forming a passageway between said chambers, a body of liquid occupying said connection, a tube formed of porcelain and having restricted aperture, said tube located in and forming part of said passageway, and means operatively associated with said member and arranged for exhausting the pressure from the pressure chamber by a movement of said member caused by the expansive action of the air retained in the retaining chamber by the liquid during a sudden reduction of the pressure in said pressure chamber.

9. An exhauster for a dry pipe sprinkler system comprising a casing forming a pressure chamber, said casing having a connection through which air under pressure is adapted to be admitted from the system, a sealed expandible air retaining chamber located in the casing and subjected externally to the pressure in the pressure chamber, a reservoir located in the casing and in communication with the pressure chamber, a restricted connection between the reservoir and the retaining chamber, a body of liquid in said connection and arranged for compressing the air within the retaining chamber relatively to the pressure within the pressure chamber, an exhaust valve controlling the flow of air from the casing, and valve actuating means operatively associated with the retaining chamber and the valve and arranged to open the valve by the expansion of the retaining chamber caused by the expansive action of the air retained in the retaining chamber by the liquid upon the occurrence of a sudden reduction of the pressure in said pressure chamber.

10. An exhauster for a dry pipe sprinkler system, comprising a casing forming a pressure chamber and having a connection through which air under pressure is adapted to be admitted from the system, a sealed expandible air retaining chamber located in the casing and subjected externally to the pressure in the pressure chamber, a reservoir located in the casing and in communication with the pressure chamber, a restricted connection between the reservoir and the retaining chamber, a body of liquid in said connection and arranged for compressing the air in the retaining chamber relatively to the pressure within said pressure chamber, an exhaust valve located in the casing and controlling the flow of air from the pressure chamber, a valve opening member movably mounted adjacent to the exhaust valve, a latch lever arranged for detachably engaging the valve opening member, a spring tending to move the valve opening member when the latter is released from said lever and for opening the valve, and means operatively associated with the retaining chamber and said lever for moving the lever by the expansion of the retaining chamber upon the occurrence of a sudden reduction of the pressure in the pressure chamber.

11. An exhauster for a dry pipe sprinkler system, comprising a casing forming a pressure chamber and having a connection through which air under pressure is adapted to be admitted from the system, a sealed expandible air retaining chamber located in the casing and subjected externally to the pressure in the pressure chamber, a reservoir located in the casing and in communication with the pressure chamber, a restricted connection between the reservoir and the retaining chamber, a body of liquid in said connection and arranged for compressing the air in the retaining chamber relatively to the pressure in the pressure chamber, an exhaust valve seat surrounding an aperture through which air may flow from the pressure chamber, a clapper movable to and from said seat, a latch lever operatively associated with the retaining chamber and movable by the expansion of the latter by excess pressure in the retaining chamber, a valve clapper opening member movably mounted within the casing, a part upon said opening member normally located in spaced relation to the clapper, cooperating parts upon the latch lever and said opening member and arranged for detachably holding the latter out of engagement with the clapper, and a spring tending to move said opening member into engagement with the clapper and the latter from said seat when said opening member is released from the latch lever.

12. In a combination exhauster and accelerator for a dry pipe valve with an intermediate chamber, a casing having an inlet chamber and a pressure chamber, a diaphragm movably mounted upon the casing and separating said chambers, a connection through which air under the system pressure is adapted to be admitted to said inlet chamber, means forming a restricted connection between said chambers, a sealed retaining chamber located in said pressure chamber, a member movably mounted upon said retaining chamber and subjected externally to pressure within said pressure chamber, a reservoir located in said pressure chamber and open to the pressure in the latter, a restricted connection between the reservoir and the retaining chamber, a body of liquid in said connection and arranged for compressing the air in the retaining chamber, an

- exhaust valve upon the casing for exhausting the air from said pressure chamber, means adapted to form a communication between said valve and the dry pipe intermediate chamber, valve actuating means operatively associated with said member mounted upon the retaining chamber and with said valve and operable by the expansion of the retaining chamber, a drain valve located in said inlet chamber, and a connecting part between said diaphragm and the drain valve arranged for opening the drain valve when the diaphragm is moved by excess pressure remaining in the inlet chamber after the exhaust valve has been opened.
- 15 13. In a combination exhauster and accelerator for a dry pipe valve with an intermediate chamber, a casing formed of upper, lower and intermediate sections, means detachably securing said sections together, a diaphragm movably mounted between the lower and intermediate sections and forming an inlet chamber in the lower section and a pressure chamber in the upper and intermediate sections, means forming a restricted connection between said inlet and pressure chambers, said casing having a connection through which air under the system pressure is adapted to be admitted to said inlet chamber, a sealed receptacle located in the pressure chamber, means detachably mounting said receptacle upon

one of said sections, a reservoir located in said pressure chamber, a body of liquid in said reservoir, a connection having a restricted passageway between said reservoir and said receptacle, a flexible member upon the receptacle and responsive to pressure in the pressure chamber and to pressure retained in the receptacle by the liquid, an exhaust valve adapted to be connected with the pressure chamber, a pipe connection between said valve and the dry pipe intermediate chamber, a 10 clapper arranged for opening and closing the exhaust valve, a clapper opening member, a bearing located in a fixed position within the casing, a shaft upon said bearing upon which shaft the clapper and clapper opening member are pivotally mounted, a spring tending to rotate said opening member into engagement with the clapper for opening the exhaust valve, a latch lever operatively associated with said flexible member, said lever detachably associated with the clapper opening member, a drain valve located in said inlet chamber, and a connecting part between said diaphragm and the drain valve arranged for opening the latter when the diaphragm is moved by excess pressure remaining in the inlet chamber after the exhaust valve has been opened.

WILLIAM B. GRIFFITH.
DAVID ARTHUR KELLER.
